Primary Examiner — Sandra Morris

CLAIM

The ornamental design for an advertising toy, as shown and described.

DESCRIPTION

FIG. 1 is a perspective view of an advertising toy showing my new design;

FIG. 2 is a front elevational view thereof;

FIG. 3 is a top plan view thereof;

FIG. 4 is a right side elevational thereof;

FIG. 5 is a rear elevational view thereof;

FIG. 6 is a bottom plan view thereof; and,

FIG. 7 is a left side elevational view thereof.

The broken lines shown on the figures are for illustrative purposes only and are hereby disclaimed as forming no part of Applicant's claimed invention.
